(57) CLAIM

The ornamental design for a napkin with pattern, as shown and described.

DESCRIPTION

FIG. 1 is a front view of a napkin with pattern showing our new design; and,

FIG. 2 is a front view thereof in a folded configuration. The dash dot dash broken lines surrounding FIG. 1 depict the boundaries of the claim and form no part thereof. The dash dot dash broken lines around and within FIG. 2 are a second view of the boundaries found in FIG. 1 and form no part of the claimed design.
